UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

LOW-PRESSURE STEAM-TURBINE.

1,089,710.

Specification of Letters Patent. Patented Mar. 10, 1914.

Application filed October 21, 1912. Serial No. 726,867.

To all whom it may concern:

Be it known that I, OSCAR JUNGGREN, a citizen of the United States, residing at Schenectady, county of Schenectady, State 5 of New York, have invented certain new and useful Improvements in Low-Pressure Steam-Turbines, of which the following is a specification.

This invention relates to low-pressure 10 elastic fluid turbines, and its object is to provide for an economical and efficient utilization of the steam when large quantities are used and expanded down to a very low absolute pressure.

15 The source from which the low pressure steam is derived is unimportant. It may be the exhaust from a high pressure turbine or from a reciprocating engine, or it may be derived from a heating plant or some other 20 industrial system in which a large quantity of steam is required; or from a combination of any two or more of these sources.

25 My invention contemplates the utilization of say two hundred thousand pounds of steam per hour, taking it from its source at or near atmospheric pressure and extracting from it practically all of its energy. The volume of a given weight of steam at low pressures is very great. One pound of water 30 evaporated into steam at 215 pounds gage pressure occupies about 123 cubic feet. Expanded down to 22 inches vacuum it fills about 5800 cubic feet or 47 times its volume at 215 pounds. At 26 inches of vacuum it 35 has nearly doubled, being about 11,000 cubic feet, while at 29.1 inches vacuum, that is, at about .4 pounds absolute pressure it fills about 50,000 cubic feet, or some 406 times its volume at 215 pounds. It is therefore evident 40 that when a high vacuum can be obtained, the lower stages of the turbine must have enormous capacity to accommodate the vastly increased bulk of steam. Attempts have been made to meet this situation by 45 dividing the low pressure steam between two similar stages, usually so arranged that the steam flows in opposite directions through said stages, in order to balance the thrust on the shaft. But the ordinary di- 50 vided flow turbine is incapable of handling the big volume of steam in the higher portions of a good vacuum unless it is operated at very high speed, and the object of my invention is to provide for a safe utilization of 55 large amounts of low pressure steam with-

out unduly enlarging the diameter of the turbine, or the length of the buckets, or operating the machine at dangerous speeds. Enlargement of the turbine would be expensive not only in cost of manufacture but 60 also in the matter of space in the power station, while unduly long buckets or abnormally high speeds would also entail costly construction as well as serious problems of operation and maintenance. I solve the dif- 65 ficulty in what may seem to be a simple manner, but one which, so far as I am aware, is novel. After leading the low pressure steam through the first few stages of a divided flow turbine, it is directed at each 70 end of such turbine against bucket wheels operating in parallel, so that without any excessive increase in the diameter of said wheels, or unwieldy lengthening of the buckets, the available bucket area is dou- 75 bled in that stage. In effect it amounts to another division of each subdivision of the divided flow turbine, so that during the concluding portions of its passage the steam has four parallel paths in place of two. 80

The accompanying drawing is a somewhat diagrammatic illustration of a turbine embodying my invention.

The machine illustrated is of the Curtis type, and has a horizontal shaft 1 journaled 85 in pillowblocks 2 at the ends of the casing 3. Low pressure steam is supplied to said casing from any suitable source; such as high pressure stages operating on the same shaft 1, a high pressure reciprocating engine, or 90 any other machine or apparatus from which high pressure steam exhausts at a comparatively low gage pressure. This steam is delivered to the chamber 4 in the casing 3, from which it flows through oppositely-facing nozzles 5 to two bucket wheels 6, 6' mounted on the shaft 1. From each bucket wheel the steam proceeds through a plurality of stages 7, 7' whose number may be varied to suit the requirements of any particular case. By the time the steam arrives at stages 8, 8' it has expanded to such a point that I find it economical to subdivide it again. Accordingly it passes not only to the nozzles 9, 9' but also flows through passages 10, 10' which lead to nozzles 11, 11' opposite to the nozzles 9, 9', so that in this concluding portion of its flow the steam is directed against bucket wheels 12, 13, 12', 13' operating in parallel. In connection 110

with this arrangement it will be noted that the final stages 12, 13, and 12' and 13' are located in housings formed by the dividing walls 15, 15', the top, sides and ends of the 5 casing 3, and the caps 16, 16', the flow of steam being restricted and diverted into the outer nozzles 11 and 11' by the annular rings 17, 17'. The passages 10 and 10' are thus continuous around the periphery of the 10 bucket wheels 12, 13, and 12', 13', and are interrupted only at the base where the final stages exhaust into the condenser outlets 14 and 14'. By this arrangement substantially equal quantities of steam are fed to 15 each side of the divided final stages and a much larger quantity of steam can be handled by a given size of bucket wheel. Considered from another view point, I divide my turbine casing into three compartments, 20 the central compartment 4 being a closed continuous annular chamber, while the compartments 10 and 10' are continuous annular chambers except where interrupted by the openings leading to the outlets 14 and 14'. 25 This arrangement is equivalent to doubling the length of the blades on wheels 12, 12', but is greatly superior to such a construction, not only in economy of space and simplicity of manufacture, but also in operation and maintenance: for example, by 30 reason of reduced strains on the buckets. From the wheels 12, 13, 12', 13' the steam passes to the outlets 14, 14' leading to the condenser, in which a high vacuum is maintained. 35 This machine will handle very large quantities of steam at the vast volume due to a vacuum of say 29.1 inches, thus extracting almost the last ounce of energy before it is exhausted into the condenser. 40 In accordance with the provisions of the patent statutes, I have described the principle of operation of my invention together with the apparatus which I now consider to represent the best embodiment thereof; but 45 I desire to have it understood that the apparatus shown is only illustrative, and that the invention can be carried out by other means.

What I claim as new and desire to secure 50 by Letters Patent of the United States, is:—

1. A low pressure turbine comprising a casing divided into a middle and two outer compartments, two sets of bucket wheels in said middle compartment arranged to form

successive stages of a divided flow turbine 55 and having their final stages communicating with said outer compartments, a plurality of bucket wheels in each of the outer compartments arranged in parallel as regards the flow of steam, and means for admitting 60 steam to said middle compartment.

2. A low pressure turbine comprising a casing divided into a middle and two outer compartments, two sets of bucket wheels in said middle compartment arranged to form 65 successive stages of a divided flow turbine and having their final stages communicating with said outer compartments, two bucket wheels located in each of said outer compartments, oppositely facing nozzles for directing steam to said last named bucket 70 wheels and means for admitting steam to said middle compartment.

3. A low pressure turbine comprising a casing divided into a middle and two outer 75 compartments, two sets of bucket wheels in said middle compartment arranged to form successive stages of a divided flow turbine and having their final stages communicating with said outer compartment, a plurality of bucket wheels in each of the outer compartments arranged in parallel, means for admitting steam to said middle compartment and exhaust outlets communicating 80 with each of said outer compartments. 85

4. A low pressure turbine comprising a casing, a shaft extending longitudinally of said casing, a plurality of bucket wheels carried by the central portion of said shaft, dividing walls forming a central annular 90 steam chamber, entirely surrounding said bucket wheels, nozzles carried by said dividing walls and coöperating with said bucket wheels to form successive stages of a divided flow turbine, the final stages exhausting into the spaces between each dividing wall and the end of the casing, a plurality of bucket wheels arranged in parallel as regards the flow of steam located in 95 said spaces, and an outlet communicating 100 with each of said spaces to receive the exhaust.

In witness whereof, I have hereunto set my hand this 18th day of October, 1912.

OSCAR JUNGGREN.
